UNITED STATES PATENT OFFICE.

THOMAS V. ALLIS, OF BRIDGEPORT, CONNECTICUT.

GUIDE FOR ROLLING-MILLS.

SPECIFICATION forming part of Letters Patent No. 670,654, dated March 26, 1901.

Application filed June 9, 1900. Serial No. 19,720. (No model.)

To all whom it may concern:

Be it known that I, THOMAS V. ALLIS, a citizen of the United States, and a resident of Bridgeport, in the county of Fairfield and State of Connecticut, have invented a certain new and useful Improved Guide for Rolling-Mills, of which the following is a specification.

My invention is an improvement in intermediary guides placed between heating-furnaces and rolling-mills; and it consists in certain details of construction to be more fully set forth in the following specification.

To enable others to understand my invention, reference is had to the accompanying drawings, in which—

Figure 1 is a rear elevation of a rolling-mill with my improved adjustable guide attached thereto and a broken view of the roll-adjusting screws. Fig. 2 is a side elevation of one of the roll-housings and a sectional view of the rolls through line *a* of Fig. 1; also, a broken view of the front or delivery end of a furnace. Fig. 3 is a detached upper plan view of the guide-frame and sectional view of two of the operating-levers; also, a broken view of a metal strip within the guide. Fig. 4 is an upper plan view of the interior of the guideway, with a broken view of a metal strip therein. Fig. 5 is a broken detail view of the locking-lever and trip-lever adapted to engage therewith. Fig. 6 is a detail broken side elevation of one of the side guides or jaws. Fig. 7 is a broken detail view of the floor and upper guide for the metal strip.

The construction and operation are as follows:

1 and 1^a are the roll-housings, and 2 2^a the rolls, of an ordinary rolling-mill. The framework of the guiding device comprises the lower part 3 and the cap 4, connected together by the screws 5. When the said cap is attached, the spaces 6 and 7 are formed, in which operate the side guides or jaws 8 and 9, having the grooves 8^a and 9^a to engage with the edges of the metal strip fed through the guide to the rolling-mill. It will be understood, however, that these side guides or jaws need not crowd hard against such metal strip, but simply lie close enough thereto to keep said strip in perfect longitudinal alinement with the furnace and at right angles with the rolls.

10 is the upper guide for the metal strip, detachably connected with the cap 4 by means of the web 10^a. 11 is the floor, on which the metal strip rests, and it is detachably connected by the web 11^a. The receiving ends of the said floor 11 and the upper guide 10 are flared, as shown at Fig. 7, to freely admit the stock from the furnace. These said parts 10 and 11 are sufficiently narrower than the metal strip so that the side guides or jaws will in operation not come in contact with such parts.

The side guides or jaws 8 and 9 are arranged to have a parallel movement by means of the links 12, 13, 14, and 15, Fig. 4. One end of these links is journaled to the pins 16, 17, 18, and 19, anchored in the lower part of the box or frame 3, which pins extend through the cap 4. The other end of said links is pivotally supported on the pins 20, 21, 22, and 23, anchored in the said side guides or jaws. 24 and 25 are recesses in the side and near the rear end of these guides or jaws for the links 12 and 14, while the large transverse opening or slot 26, Fig. 6, extends through the forward end of said guides for the accommodation of the toes 27 and 28 and also to receive the links 13 and 15, presently to be described. The said toes are firmly secured to the vertical pins 29 and 30, pivotally supported in said guides or jaws, and such pins extend upward through the radial slots 31 and 32 of the cap 4, as shown at Fig. 3. The outer ends of the arms 33 and 34 are firmly secured to the upper ends of pins 29 and 30, while their inner ends are pivoted to the pin 35 of the sliding bar 36, operating in the standard 37. 38 is an adjusting-screw in the standard 39 for limiting the backward travel of said sliding bar. 40 is a forked arm projecting from the cap 41 of standard 37, and 42 is a bell-crank lever mounted in said forked arm. The vertical arm of this bell-crank lever extends downward through a slot (not shown) near the rear end of said sliding bar, while the horizontal arm of said bell-crank lever carries the adjustable weight 43.

By means of the mechanism just described the inward pressure on the toes 27 and 28 is regulated and such pressure increased or decreased by simply shifting this weight 43 on its support. When the metal strip 44 is to be

entered into the guideway, the side guides or jaws 8 and 9 will be moved back and out of engagement with said strip. The toes 27 and 28, however, project into the feedway or feeding-line of the metal strip and engage directly with said metal strip, so as to guide it into the bight of the rolls and at right angles thereto. After the entering end of said strip projects through said rolls the side guides 10 are moved inward toward the strip, so as to maintain the initial alinement already established by the toes 27 and 28, in the following manner:

45 is a rock-shaft journaled in the standards 15 46 and 47.

48 and 49 are arms resting on the outer-surface of the cap 4 and swiveled by one end to the pins 50 and 51, depending from said rock-shaft, and these arms are connected to the 20 vertical pins 52 and 53 of the side guides or jaws 8 and 9, which pins project through the radial slots 52^a and 53^a. These radial slots, as well as the radial slots 31 and 32, are merely intended to afford plenty of room for 25 the pins projecting therethrough to freely operate therein.

54 is a projection of the rock-shaft 45, to which are secured the levers 55 and 56 by means of the bolt 57. The lever 55 is pivotally 30 connected to one end of the horizontal operating-rod 58. This rod is provided with the threaded end 58^a, and such threaded end is supported in the tilting box 59, which box has a vertical tilting movement on the pins 60. 35 61 is a cross-bar secured to the rods 62, and 61^a is a projection of said bar, and in such projection the said tilting box 59 is pivotally hung.

The upper end of lever 56 is pivoted to 40 the horizontal locking-lever 63. (See also Fig. 5.) 63^a is a catch on said locking-lever and is adapted to engage with the upper end of the trip-lever 64. This latter lever is mounted in a forked opening in the lower end 45 of the projection 61^a and is pivotally supported on the pin 65. The horizontal arm 64^a of the trip-lever carries the adjusting-screw 66, adapted to engage with the free end of the locking-lever 63 and release said lever 50 in the manner presently to be described. The lower end of said trip-lever is provided with the toe 67, which hangs directly in the path of the metal strip 44 as it emerges from the reduction-rolls onto the surface-guide 68. 55 This toe is attached to the short leg 64^b of the trip-lever, which leg is supported to said lever by the frictional hinge 69. When, therefore, the metal strip is fed from the furnace 70, Fig. 2, into the guideway, it is first brought 60 under the influence of the toes 27 and 28, Fig. 4, which toes, as before stated, guide it into the bight of the rolls. After passing through said rolls the end of said strip strikes the toe 67 of the trip-lever and, tilting the same on 65 its pivotal support, will thus cause the adjusting-screw 66 to engage the free end of the locking-lever and release its engagement with

the trip-lever. The locking-lever being thus released will be carried back in the direction of arrow *a'* by means of a weight (not shown) 70 attached to one end of the cord 71, connected to the rod 58. This return movement will rotate the rock-shaft 45 in the direction of arrow *b*, which will, as before described, carry the guides or jaws 8 and 9 in toward the strip, 75 and thus prevent its deviating from the straight line established by the toes 27 and 28. When, therefore, the said metal strip has passed through the rolls, the locking-lever is again brought into engagement with 80 the trip-lever to admit another strip from the furnace.

The nuts 72, mounted on the threaded end of rod 58, will be set so as to strike against the end of the tilting box 59, and thus limit 85 the backward travel of such rod, and consequently the inward travel of the guides or jaws 8 and 9. Therefore a greater or less movement of these guides or jaws is regulated by the position which said nuts occupy 90 on rod 58.

73 is an adjusting-screw pivotally supported on the lever 55, whose threaded portion engages with the threaded clamp 74 on the lever 56, so that when the throw of the 95 said guides or jaws is determined the position of lever 56 can be properly adjusted with respect to the engagement of the locking-lever 63 and the trip-lever 64.

The object of the frictional joint 69 of the 100 trip-lever is to enable the toe end 67 to be raised in case of serious buckling or accident to the passing strip. If the trip-lever were not so provided, the adjusting-screw 66 would strike against the rod 58 and break said lever; but for perfect strips the frictional joint 105 is sufficiently stiff to effect the tripping action.

It is immaterial as to how the guide-frame is supported on or near the rolling-mill. In 110 the drawings its rear end is shown supported on the clamp 75, mounted on the bar 76, while its front end is supported by the brace 77, projecting from said clamp. The rolling-mill housings prevent lateral displacement, 115 while the stop 78, projecting from the cap 79 of said clamp, will prevent its moving backward.

The purpose of the inclosed guideway represented by the box or frame 3 and its cap 4 120 is to protect thin metal plates from contact with the air on their passage from the furnace to the rolls; but an inclosed guideway, broadly speaking, is not the essential feature of my invention. In fact, the side guides or 125 jaws, toes to engage with the forward end of a metal strip to start it squarely within the bight of the rolls before the side guides are brought forward, and the mechanism for operating said guides and toes could just as well 130 be used on an open guideway.

A spring could be substituted for a weight to operate the mechanism for carrying the side guides or jaws up to the metal strip. In

fact, the peculiar construction of all the operating mechanism could be varied without departing from the spirit of my invention, which consists, essentially, in suitable means located near the rolls for initially centering and guiding the metal strip into the bight of the rolls and side guides or jaws to be afterward brought into engagement therewith.

While I show a furnace in connection with the guideway, it will be understood that my invention is applicable to the ordinary processes of rolling metal passed to the rolls by hand.

Having thus described my invention, what I claim as new, and desire to secure by Letters Patent, is—

1. The combination with a rolling-mill, of a guideway adapted to receive a metal strip preparatory to its entering the bight of the rolls, yielding guides or jaws adapted to engage the edges of the metal strip and centralize the same with respect to said guideway, auxiliary side guides or jaws adapted to be brought forward and preserve the alinement of said strip after it has entered into the bight of the rolls, for the purpose set forth.

2. The combination, with a rolling-mill, of centralizing-guides pivotally supported in a feedway in close proximity to the rolls, the supports for said guides linked together so that said guides move in unison and thereby exert a yielding pressure on the edges of a metal strip being fed into the bight of said rolls so as to centralize said strip with respect to its feeding-line and thus cause said strip to enter said rolls at right angles thereto, for the purpose set forth.

3. The combination with a rolling-mill, of initial edge-guides located in close proximity to the rolls and adapted to exert a yielding but centralizing pressure on the edges of a metal strip being fed into the bight of the rolls and thus give an initial alinement thereto, combined with supplemental or auxiliary edge guides or jaws adapted to be brought forward and preserve the alinement established by said initial guides, for the purpose set forth.

4. The combination, with a rolling-mill, of edge guides or toes adapted to engage the edges of a metal strip being fed into the bight of the rolls, pivotal supports for said guides, said supports linked together so that said guides will move in unison and exert a yielding centralizing pressure on said metal strip and thus establish its feeding-line at right angles to the rolls, for the purpose set forth.

5. The combination with a rolling-mill, of yielding edge-guides adapted to engage the edges of a metal strip and exert a yielding but centralizing pressure thereagainst so as to guide the same into the bight of the rolls, means substantially as shown whereby such yielding and centralizing pressure is effected, auxiliary side guides or jaws adapted to be brought forward toward said metal strip to maintain the alinement effected by said flexi-

ble guides, means for effecting the movement of said auxiliary guides, for the purpose set forth.

6. The combination with a rolling-mill, of yielding centralizing edge-guides adapted to engage the edges of a metal strip and guide it into the bight of the rolls, means for exerting a pressure on said guides, auxiliary guides or jaws having a parallel movement to and from said metal strip and adapted to be brought forward to maintain the alinement already established by said flexible guides, means substantially as shown for operating said auxiliary guides or jaws, means for supporting said metal strip, for the purpose set forth.

7. The combination with a rolling-mill, of yielding centralizing edge-guides adapted to exert a yielding pressure on a metal strip being fed into the rolls and to guide the same therein, auxiliary edge guides or jaws adapted to be brought forward to the metal strip and maintain the alinement established by said flexible guides, means whereby said auxiliary guides or jaws are held back until after the said strip has projected through the rolls, a trip-lever adapted to be engaged by the forward end of said strip and release said auxiliary guides or jaws, for the purpose set forth.

8. The combination with a rolling-mill, of a guideway located near the rolls, yielding centralizing edge-guides adapted to engage the edges of a metal strip being fed into the rolls and exert a yielding but centralizing pressure thereagainst, auxiliary guides or jaws having a parallel movement, means for effecting such movement, means for locking said auxiliary guides or jaws in open position until after the end of the metal strip has projected through the rolls, a trip adapted to be engaged by the end of said strip and release said auxiliary guides or jaws, for the purpose set forth.

9. The combination with a rolling-mill, of a guideway, yielding centralizing edge-guides adapted to engage a metal strip in close proximity to the rolls and guide the same thereto, auxiliary guides or jaws adapted to maintain the alinement already established by said flexible guides, said flexible guides mounted on said auxiliary guides or jaws, means for operating the former independent of the latter, for the purpose set forth.

10. The combination with a rolling-mill, of a guideway for conducting metal strips to the rolls, edge guides or jaws having a parallel movement and located in such guideway, said guides or jaws adapted to be thrown out of contact with a metal strip until after it has entered into the bight of the rolls, yielding guides located near the forward end of said parallel operating guides or jaws so as to exert a yielding but centralizing pressure on said strip and guide it into the bight of the rolls, means substantially as shown for operating both of said guides, for the purpose set forth.

11. The combination with a rolling-mill, of a guideway having a support for metal strips to be fed into the rolls, parallel operating side guides or jaws carrying yielding toes or initial guides near their forward ends adapted to bear against the edges of a metal strip and centralize said strip with respect to said guideway so as to cause said strip to enter the bight of the rolls at right angles thereto, means for locking said parallel operating guides or jaws in open position and means for automatically unlocking the same and carrying said guides or jaws forward toward the metal strip so as to maintain the alignment already established by said toes, for the purpose set forth.

12. The combination with a rolling-mill, of a guideway having a support for metal strips adapted to be fed into the rolls, edge guides or jaws mounted in said guideway, means whereby a parallel movement is imparted to said guides or jaws actuating them to and from a metal strip on said support, said guides

or jaws carrying yielding guides at their forward ends adapted to engage the edges of a metal strip and centralize the same with respect to the guideway when the first-mentioned guides or jaws are in open position, and means for maintaining the same in open position, a trip-lever forward of the rolls adapted to be engaged by the metal strip and release said guides or jaws, for the purpose set forth.

13. The combination, with a rolling-mill, of a guideway for conducting metal strips to the rolls, a pair of edge guides or jaws linked by each end to said guideway so that said guides or jaws will have a parallel movement to and from each other, for the purpose set forth.

Signed at Bridgeport, in the county of Fairfield and State of Connecticut, this 8th day of June, A. D. 1900.

THOMAS V. ALLIS.
